(57) **CLAIM**

The ornamental design for a cleaning caddy as shown and described.

DESCRIPTION

FIG. 1 is a perspective view showing the new design for a cleaning caddy;

FIG. 2 is a left view thereof;

FIG. 3 is a right view thereof;

FIG. 4 is a back view thereof;

FIG. 5 is a front view thereof;

FIG. 6 is a top view thereof;

FIG. 7 is a bottom view thereof; and,

FIG. 8 is a bottom perspective thereof.

The portions of the cleaning caddy in FIGS. 1-8 shown in broken lines are included to show features that form no part of the claimed design.
